DISPLAY RACK

Eugene Kleinman, Montvale, N.J., assignor to Kayser-Roth Corporation, New York, N.Y.

Filed July 27, 1972, Ser. No. 275,856

Term of patent 14 years

Int. Cl. D20—02

U.S. Cl. D6—189

FIG. 1

FIG. 2

FIG. 3

FIG. 1 is a front and right side perspective view of a display rack embodying my new design;

FIG. 2 is a top plan view thereof;

FIG. 3 is a bottom plan view thereof;

FIG. 4 is a left side elevational view thereof; and

FIG. 5 is a rear elevational view thereof.

I claim:

The ornamental design for a display rack, as shown.
